UNITED STATES PATENT OFFICE

2,583,926

DISPLAY DEVICE

John H. Beyer, Forest Hills, N. Y.

Application July 27, 1949, Serial No. 107,069

2 Claims. (Cl. 40—10)

1

The invention relates to an interchangeable two-member display device wherein one member is a stand having obtuse angled slots and the removable member is formed of a display card or the like and has tabs and linear tab extensions, whereby the tab extensions may be turned to one side to permit insertion of the tabs into the angular slots in the stand, the inherent tendency of the tab extensions to regain their linear position causing frictional engagement of the two members as a unit.

An object of this invention is to provide a modified display card having tabs and tab extensions of lesser height than the tabs, providing a clearance space between the lower face of the display card and the tab extension equal to the thickness of the body of the stand, thereby to permit bending the tab extensions below the stand body and cause a positive interlock between the display card and the stand.

Another object of this invention is to provide a two-member display device which is easily attached and which is easily detached from each other and which is of neat and pleasing appearance.

Another object of this invention is to provide a two-member display device which can be detached from each other and compactly boxed for shipment or bulk storage.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of a display card forming one element of this invention.

Figure 2 is a cross-sectional view of the assembled display device, the section being taken on line 2—2 in Figure 3.

Figure 3 is a bottom plan view of the assembled display device shown in Figure 2, part of the display card being broken away to show an obtuse angled slot passing through a stand forming part of the display device.

Figure 4 is a front elevation of a modified display card having tabs and tab extensions of lesser height than the tabs to permit bending of the tab extension below the stand.

Figure 5 is a perspective view of the modified and assembled display device having a positive

interlock between the display card and the stand.

In the illustrated embodiment of the invention, the numeral 10 indicates an interchangeable display assembly comprising a display card 11 having an elongated linear base 12 and tabs 13 extending lengthwise of and below its base portion.

The tabs 13 have vertical score lines 14 defining tab extensions 15 which terminate at the lower edge 16 of the display card 11. The display card 11 is of ornamental form and may have an illustration 17 suitably printed or formed thereon.

The interchangeable display 10 comprises a stand 18 having through slots 19. The dimensions 15 of the slots are made so that the walls defining the slots frictionally engage the tabs 13 of the display card 11.

The slots 19 are positioned lengthwise of the stand 18 and have angular wall extensions 20 of the same width. An obtuse angle is formed between the walls of the respective slots, the angle being preferably about one hundred and ten degrees.

The height of the tabs 13 is the same as the thickness of the stand 18 and when the tabs are inserted into the obtuse angled slots 19, 20, the bottom of the display card 11 is flush with the bottom of the stand 18.

For the purpose of positively interlocking the display card and the stand in unitary relation and so as to permit variously illustrated display cards to be selectively interlocked with the stand, there is provided a modified structure shown in Figures 4 and 5, wherein a display card 21 has an elongated linear base 22 and tabs 23 extending lengthwise of and below its base portion.

The tabs 23 have vertical score lines 24 defining tab extensions 25 which terminate at the lower edge 26 of the display card 21.

Each tab extension 25 is of lesser height than a tab 23 and provides a clearance space between the lower face of the display card 21 and the tab extension 25 equal to the thickness of the body of a stand 27 which is designed to coact with the modified display card 21.

The stand 27 has a flat horizontal body 28 and vertical flanges 29 of a height to permit bending the tab extensions 25 in angular relation with the tabs 23, below the stand body 28, and cause a positive interlock between the display card 21 and the stand 27.

It is to be noted that the display cards have a degree of resiliency whereby the tab extensions have an inherent tendency to regain their linear position and thereby retain said card and stand

in frictional engagement as a two-member unit.

This resilient effect is permitted to operate with the disclosure shown in Figures 1 to 3 inclusive. With the disclosure shown in Figures 4 and 5, the tab extensions are bent beyond their elastic limit and cannot return to normal linear position and thereby function to interlock the display card and the stand.

In accordance with the patent statutes I have described and illustrated the preferred embodiment of my invention, but it will be understood that various changes and modifications can be made therein without departing from the spirit of the invention as defined by the appended claims.

I claim:

1. In an interchangeable display including a display card having an elongated linear base and downwardly extending tabs and a stand, co-operating fastening means between said display card and stand comprising linear extensions of said tabs, and obtuse angled slots formed in the stand adapted to receive and frictionally engage the sides of said tabs, the said tabs having linear extensions foldable into obtuse relation with the said slots to enter therein, the said display card having a degree of resiliency whereby the tab extensions have an inherent tendency to regain their linear position and thereby retain said card and stand in frictional engagement as a 30 two member unit.

2. In an interchangeable display of the character described including a display card having a pair of downwardly extending and spaced tabs and including a stand, each of said tabs having a linear extension, a pair of obtuse angled slots adapted to receive and frictionally engage the sides of said tabs, each of said tabs having linear extensions foldable into obtuse relation with each of said slots and to enter the same, the said display card having a degree of resiliency whereby each tab extension has an inherent tendency to regain its linear position and thereby retain said card and stand in frictional engagement as a two member unit.
